UNITED STATES PATENT OFFICE.

OSCAR M. FULWIDER AND ALBERT E. BURRUSS, OF NORFOLK, VIRGINIA.

BARREL-HEAD.

1,377,334.

Specification of Letters Patent. Patented May 10, 1921.

Application filed March 23, 1920. Serial No. 368,003.

To all whom it may concern:

Be it known that we, OSCAR M. FULWIDER and ALBERT E. BURRUSS, citizens of the United States, residing at Norfolk, in the county of Norfolk and State of Virginia, have invented certain new and useful Improvements in Barrel-Heads, of which the following is a specification.

Our invention relates to heads for barrels or other receptacles.

The object of the invention is to provide a barrel head that may be quickly removed entirely at will, or a certain part of the same when it is desired to bail out the contents or take any article therefrom a little at a time and afterward to close the opening, to exclude dust and air, until there is an occasion to repeat the operation.

A further object is to prevent injury to the barrel or receptacle and the consequent deterioration of the contents thereof.

Further objects and advantages will be more fully described herein and specifically pointed out in the annexed claim recourse being had to the accompanying drawing forming a part of this specification in which:

Figure 1 is a plan of the barrel and our improved head without the cross or holding bar.

Fig. 2 is a plan of the complete barrel head with its holding bar and straps.

Fig. 3 is a cross section of the upper part of a barrel showing our improved barrel head taken on the line 3—4 in Fig. 2.

Fig. 4 is a cross section of the head without the bar and its straps taken on the line 1—2 in Fig. 1.

Fig. 5 is a fragmentary enlarged section of the lap or rabbet joints of the head showing the beading thereon and packing to prevent leakage.

Fig. 6 is a side elevation of one of the holding straps for the cross bar, and its hinged or movable portion.

Fig. 7 is a plan of one member of the central or movable portion of the head showing the hinge joint, and Fig. 8 is an enlarged fragmentary section of the hinge joint of the central or movable head member or members in detail.

In the drawing like reference numerals indicate similar parts in all the several views:

1 represents the top part of a stave barrel, 2 the edge or chine, and 2^a is the annular

groove around the same for the edge of the circular head to engage and be secured in position, as in ordinary practice.

3 are the outer and 4 are the central or 60 movable head members, the latter being slidably and liftably mounted on the former.

Both the members described, have the usual double angle or tapered edge 3^a so that the entire circular head may fit in the annular groove 2^a in the chine 2.

Two sides and one end of the central head members 4, and one side of the outer members 3, are provided with lapped or rabbet joints 4^a for the slidable mounting of the 70 head members 3 and 4.

In order to prevent leakage through the rabbeted joints we provide a bead or beading 5, which fits into a corresponding groove in the opposite rabbeted member as shown in 75 Figs. 3 and 4. As an additional precaution against leakage, we apply thin sheet packing 5^a, (Fig. 5), on the surface of the rabbet joints, as shown.

One or both of the central members 4 may 80 be hinged as at 6 in Fig. 8, 7 being the hinge wire or pin, 8 the stump or prop joint, taken with the quarter round 9, forms a joint similar to that used on drop leaf tables.

The hinge wire 7 extends outward from 85 the edge of the central member or members so that the protruding ends of the wire may engage suitable orifices in the outer members 3, as at 7^a in Fig. 7.

10 is a screw head on one of the central 90 members so that they may be lifted by inserting any convenient bar or board under the head and the same may be raised by prying.

11 and 12 are the left and right hand metal 95 or wood straps, respectively, and are screwed on the outer head members so that the hereinafter named bar may pass through them and be locked by it. One of the straps, as at 12, is adapted to be hingedly connected 100 so that one part 13 may swing aside from the other, as shown by the dotted lines in Fig. 2 and in full lines in Fig. 6.

13^a is the hinge pin or screw for the movable strap member and 14 is the diagonal 105 joint between the fixed and movable part of the strap 13.

The entire head is held in place by the cross bar 15 placed at right angles to the head members 3 and 4 and having its two 110 ends passing through and held by the straps 11 and 12.

16 is a locking strip along a part of the length of the bar 15 or may be formed from one piece, the two ends of which act as a lock to prevent the bar from having a lateral 5 movement and thus causing it to become displaced.

The movable part of the strap 13 may be held securely in place, as in Fig. 2 by the full lines, by means of a suitable lock.

- 10 To open the closed barrel equipped with our improved head, it is only necessary to throw aside the movable part 13 of the strap 12, lift off the bar 15 and take out the entire head or any part thereof, for instance, the 15 hinged members 4, if they are so fitted, by simply lifting them by means of the bolt head 10 or by any other means.

We claim:

A device of the class described and in com-

bination with a barrel, of a head therefor 20 comprising fixed outer members and hinged central members, rabbeted and beaded packing fitted means between said members, a detachable bar at right angles to the members for holding the same in position, holding straps for said bar, one of the said straps adapted to be hingedly fitted to permit a part of the same to be swung aside to release the bar from the outer and central members. 25

In testimony whereof we have hereunto 30 affixed our signatures in the presence of two witnesses.

OSCAR M. FULWIDER.
ALBERT E. BURRUSS.

Witnesses:

WALTER B. BURRUSS,
A. LOTT.
